UNITED STATES PATENT OFFICE.

JOSEPH L. WRIGHT, OF CLEVELAND, OHIO, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,249,582.

Specification of Letters Patent. Patented Dec. 11, 1917.

Application filed November 11, 1912. Serial No. 730,761.

To all whom it may concern:

Be it known that I, JOSEPH L. WRIGHT, a citizen of the United States, and resident of Cleveland, Cuyahoga county, State of Ohio, have invented certain new and useful Improvements in Telephone-Exchange Systems, of which the following is a specification.

My invention relates to telephone exchange systems, and especially to that class known as semi-automatic. In systems of this type automatic switches are used for interconnecting the subscribers' lines. The switches themselves are controlled by an operator who is provided with a suitable impulse device or key-board.

The object of my present invention is to provide means for operating a system of the semi-automatic class in conjunction with manual exchanges. In the present instance the automatic switching mechanism for interconnecting the subscribers of the semi-automatic exchange is located at one point, while the operators who control it are located at another point or in the same exchange containing a manual switch-board. The operators controlling the automatic switching mechanism are provided with a key-board and control circuits therefor. The calls originating at the distant semi-automatic exchange are automatically connected to the operator's key-board over special control trunks. After a connection is completed, the key-board is automatically disconnected and is ready to be used for other calls.

In trunking from a manual switch-board to the semi-automatic exchange the semi-automatic operator is provided with a special control circuit and key-board. A subscriber in a manual exchange desiring to converse with a subscriber in the semi-automatic exchange gives the desired number to the regular "A" operator at the manual switch-board who thereupon presses an order wire button leading to the semi-automatic operator, who assigns the trunk to be used. This latter operator is provided with a button and signal lamps for each trunk. The signal lamp is lighted when the "A" operator places the calling plug into the trunk jack associated with this trunk. The lighting of this lamp notifies the semi-automatic operator that the assigned trunk has been taken, by the "A" operator, and she then

presses a control button belonging to her key-set, and also the button associated with the trunk assigned. This operation causes the operator's key-board to become connected to the trunk. The semi-automatic operator now sets up the proper number on her key-board and connects the calling subscriber to the desired subscriber in the semi-automatic exchange through the automatic switches. As soon as this connection is completed, the semi-automatic operator is disconnected and the "A" operator at the manual switch-board has supervision over and controls the connection.

In trunking from the semi-automatic exchange to a manual exchange, the calls are handled as follows: The semi-automatic operator upon receiving a call from the semi-automatic exchange for a subscriber in the manual exchange, presses an order-wire button leading to an operator at the manual switch-board who assigns the trunk to be used. The semi-automatic operator sets up the number of the trunk assigned on her key-board causing a special selector switch to pick out the assigned trunk leading to the manual exchange. When this trunk is picked out, the operator at the manual switch-board receives a suitable signal associated therewith and completes the connection to the subscriber at the manual exchange in the regular manner. After the trunk has been picked out, the key-set belonging to the semi-automatic operator is disconnected.

In designing this system special provision has been made in order to render it unnecessary for the calling subscriber to give the number to more than one operator, even though the number of the desired subscriber is in another exchange. This provision has been made in order to conform with customary traffic conditions existing at present in some of the larger telephone exchanges.

It will be found after reading the specifications that different methods of handling the traffic can be made without changing the present circuits. Some of these methods will be pointed out later.

Another feature of this invention is the manner in which the operator of the semi-automatic exchange, even though located at a distant point can originate and supervise calls.

2
My invention is illustrated in the accompanying drawings wherein,

Figure 1 shows a subscriber's line and control circuit at the semi-automatic exchange.

Fig. 2 shows a primary and first selector circuit.

Fig. 3 shows a second selector circuit.

Fig. 4 shows a connector circuit with 10 party line ringing equipment.

Fig. 5 shows a subscriber's line and control circuit at the semi-automatic exchange.

Fig. 6 shows the control circuit for the key-set switches.

15 Fig. 7 shows the key-set switch and circuits of the portion at the semi-automatic exchange in which the main switching equipment is located.

Fig. 8 shows a portion of the key-set circuit located at a distant point.

20 Fig. 9 shows the operator's key-board and sending machine.

Fig. 1^b shows the arrangement for originating a call in the semi-automatic exchange 25 so as to enable reverting or special calls to be handled.

Fig. 1^a shows a line and cord circuit at the manual exchange and a portion of the trunk circuit leading to the semi-automatic exchange.

30 Fig. 2^a shows the trunk located at the semi-automatic exchange terminating in a selector switch.

Fig. 6^a shows the control circuit between 35 the trunks from the manual exchange and the key-set switches.

Fig. 3^a shows a trunk selector at the semi-automatic exchange.

40 Fig. 4^a shows a trunk from the semi-automatic exchange to the manual exchange terminating in a plug and also a subscriber's line circuit at the manual exchange.

Fig. 10 shows the arrangement of the various figures when a subscriber in the semi-automatic exchange calls for another subscriber in the same exchange.

45 Fig. 11 shows the arrangement of the various figures when a subscriber in the manual exchange calls for a subscriber in the semi-automatic exchange.

50 Fig. 12 shows the arrangement of the various figures when a subscriber in the semi-automatic exchange calls for a subscriber in the manual exchange.

55 Fig. 13 shows the arrangement of the various figures in case a subscriber in the semi-automatic exchange wishes to call some one on the same line.

60 Referring to Fig. 1, the subscriber's station at A is equipped with apparatus usual in common battery systems, and the line wires from this station terminate at the central office in a line relay 2.

65 The line relays are divided into groups, there being ten groups to each one hundred

lines. The group relay 3 is common to each group of ten line relays as shown. This relay when energized, makes the row contact in the primary switches busy, while the line relay 2 serves to render the individual test 70 contact in the primary switch busy.

The switch W is common to a group of one hundred lines and rotates in search of an idle primary trunk whenever a call in the group with which it associates is originated.

Referring to Fig. 2 the primary switch C is a two-motion switch and rotates first in a rotary direction until the row contact which designates a group of calling lines is 80 picked out, whereupon the switch ceases to rotate and steps in a vertical direction until the individual test contact is found.

The first selector switch shown at D responds to impulses from the sending device 85 and rotates in order to bring the wipers opposite the proper group of trunks leading to the second selector switches. The wipers 63 of the primary switch C and wipers 56 of the first selector switch D are joined as indicated by the heavy lines for conversational purposes. The condensers 43 and 44 respectively are inserted in the talking conductors. Relays 23 and 24 are connected respectively to ground and battery and serve 90 to furnish talking current to the calling subscriber. Relay 21 is the starting relay for the primary switch C and corresponds to relay 2, Fig. 1, as it controls the action of the operator's key-set switch, Fig. 7, in the same 100 manner that relay 2 controls the primary switch C. Relay 22 is the row test relay, while 24 in addition to being a battery supply relay also serves as the individual test relay in picking out the calling line. Relay 105 25 is operated when the key-set switch, Fig. 7, picks the trunk and remains energized while the impulses are being transmitted to prevent them being heard by the calling subscriber. Relay 27 is the test relay of the first 110 selector switch and remains energized while the switch is stepping in a vertical direction, and while the test wiper 57 comes into engagement with busy contacts. Relay 28 is actuated whenever either the rotary or vertical 115 magnets of the primary switch are operated, and also when the vertical magnet of the first selector switch is operated. The circuits of these magnets are normally completed through the back contacts of this relay 28, and so therefore the action set up between this relay and the magnets cause them to operate their respective switches.

120 The resistance coil 42 is placed in series with the rotary relay 29. This relay receives 125 impulses from the sending device and operates the rotary magnet 34 causing the switch D to rotate. The operation of the magnet 34 when it completes its stroke closes its associated contact springs and places ground 130

between the coil 42 and the winding of the relay 29, thus shunting out relay 29 and dissipating any static charge on the conductors leading to the exchange in which the sending device is located. This arrangement dispenses with the necessity for fine adjustment between the repeating relay and the magnet which it controls, for as soon as a magnet completes its work, the repeating relay is at once shunted out and all residual magnetism thereby dissipated.

Referring to Fig. 3, the second selector switch E is operated in the same manner as that of the first selector at D. It first moves in a rotary direction to pick out the group of trunks leading to connector switches and then in a vertical direction to pick out the idle trunk in the group. Relay 81 is the rotary repeating relay and is regulated by the action of the rotary magnet 85 and the resistance coil 86. 82 is the interrupter relay corresponding to relay 28, Fig. 2. 83 is the test relay, while relay 80 controls the release of the switch E.

Referring to Fig. 4, the connector switch G is provided with the wipers 390 for effecting connection with the called line and when so connected places the line cut-off relay in series with the sleeve relay 325. Relays 305 and 310 are the repeating relays and respond to impulses from the sending device. The resistance coil 370 is common to the winding of both relays and serves to regulate them in conjunction with the stepping magnets of the switch G and the stepping magnet 360 of the switch F. Relays 315 and 330 are locking or control relays. Relay 340 is the ringing relay and is operated when the connection is completed by means of the commutator 370. Relay 320 is the tip battery supply relay and responds when the called subscriber removes his receiver. Relay 345 is the busy test relay and is only actuated when a busy line is found. The action of this relay at this time closes the circuit of the release magnet 365 and connects a suitable busy tone test to the calling subscriber.

The controlling or party line distributing switch is shown at F. The contacts and wiper of the portion J cut on the generators 356, 357, 358 or 359 depending upon the number of impulses transmitted by the sending device. The contacts and wiper of the portion I serve to restore the switch to its normal or idle position. The contacts and wiper of the portion H serve to render the connector switch busy after the called party has answered by connecting ground to the test wire 306. The wiper and portion H also serve to restore the switch G after the called party hangs up his receiver, or in case the calling party hangs up his receiver when the called party fails to answer his telephone.

Fig. 5 shows the same equipment as in Fig. 1 and need not be described.

Referring to Fig. 6 the switch shown at Y corresponds to the switch W, Fig. 1, and serves to pick out an idle operator's key-set switch. The switch X is a time element control switch and only comes into action when the relays 130 and 132 have been held energized beyond the maximum time limit. The relay 132 is energized as soon as the idle key-set switch is picked out and should only remain energized long enough for the key-set switch, Fig. 7, to pick out the tenth contact in the tenth row. The magnet 77 causes the switch X to operate at each rotation of the sending device. The rotation of the sending device closes contact springs 86.

We will assume that the relays 132 and 130 have been held energized beyond the maximum time and the switch X is rotating. When the wiper α^2 reaches one of the contacts connected to the wire 139 the circuit of relay 78 is closed to ground through the contacts of relay 132. The switch X continues to step once at each rotation of the sending device and when the wiper α reaches one of the contacts to which relay 76 is connected this latter relay operates and performs the following functions: Battery is placed on the wire 149 through the wiper 95 and contacts of the lower bank of the switch W, Fig. 1, to wire 260 operating the release magnet 32 causing the switch C to restore. Ground is also placed on wire 144 through the lower bank contacts of the switch Y to 100 the release magnet 166 of the switch M, Fig. 7, causing the key-set switch to restore. Ground is also placed on the wire 148 leading to the stepping magnet 7 of the switch W, Fig. 1, through the contacts of relay 5, 105 thereby causing this switch to step forward one contact.

If the calling subscriber is connected to a primary switch C and a faulty connection takes place between this switch and the switch M, the connection is at once released thereby preventing his call being tied up. As soon as the connection first established, or partly established is released, then another primary switch or key-set switch will 115 start to complete the connection.

The switch X performs no functions in connection with regular calls and only comes into play in case of an abnormal condition.

Referring now to Fig. 7, the key-set 120 switch M acts in the same manner as the primary switch C, Fig. 2, as it first rotates to pick out the group in which the calling trunk is located and then steps in a vertical direction to pick out the individual contact 125 in the group. The tip and sleeve conductors 150 and 151 respectively are connected to the tip and sleeve conductors, Fig. 2, by wipers 167. Relay 153 is the row test relay and is connected to the row test wiper 168. 130

Relay 154 is the individual test relay. Relay 152 is the starting relay and is energized as soon as the switch Y, Fig. 6, picks out the idle switch M. Relay 163 is the interrupter 5 relay actuated by the rotary and vertical magnets 165 and 164. Relay 179 is energized as soon as the row test relay 153 is energized and connects one terminal of relay 180 to battery after relay 152 is deenergized, 10 the other terminal of this relay 180 is connected permanently to the tip conductor 150. Relay 190 has its circuit completed after the switch M rotates and after relay 152 becomes deenergized. The energizing of relay 190 15 at this period places the relay 173 in series with relay 156, Fig. 8.

The three conductors 150, 151 and 175 extend to the key-set circuit located at a distant exchange. The impulses are transmitted over the conductors 150 and 151, while conductor 175 serves for signaling and release purposes.

The relay shown at 700 is a control relay and is used by the operator who handles 25 calls from subscribers in the manual exchange to subscribers in the semi-automatic exchange. The only difference between the circuits of the various key-boards is the addition of this special relay and in fact, all 30 of the key-boards could be provided with this control circuit. The only function performed over this circuit is to open or close the starting circuit of the relay 152, Fig. 7. The details in connection with this circuit 35 will be brought out in describing a call from the manual to the semi-automatic exchange.

Referring to Fig. 8, relay 156 is the signal relay and when actuated closes the circuits of the signal lamps 243 and 244, Fig. 9. Relays 157 and 162 are connected in series and 40 serve for starting a call when the button 247 is pressed. Relay 155 is the listening relay and when actuated by the button 248 being pressed connects the operator's telephone 45 set across the tip and sleeve conductors 150 and 151. The action of relay 155 disconnects relay 156. Relay 185 is the interrupter relay for the magnet 161 which controls the shifting switch shown at portions N, O and 50 P. Relay 158 is the release relay and comes into action after all the impulses have been transmitted. Relay 159 is used for trunk calls and controls the action of the shifting switch so that for trunk calls fewer rotations of the sending device are required.

The stepping magnet 161 is operated once at each rotation of the sending device and cuts on the impulses from the key-board and sending device in a predetermined order as 55 follows: At the first rotation impulses corresponding to the thousands are sent over the tip side of the trunk. At the second rotation a single test impulse is sent over the sleeve side of the trunk. At the third 60 rotation impulses corresponding to the hun- 65

dreds are sent over the tip side and at the fourth rotation a single test impulse is sent over the sleeve side of the trunk. At the fifth rotation selective ringing impulses are sent over the tip side of the trunk and at 70 the sixth rotation the tens impulses are sent over the sleeve side of the trunk. At the seventh rotation the units impulses are sent over the tip side and at the eighth rotation impulses a single test impulse is sent over 75 the sleeve side of the trunk. At the next rotation of the sending device the wiper of the portion P passing over the bank of contacts closes the circuit of relay 158 causing the shifting switch to rapidly rotate until it 80 reaches its normal position. The energizing of relay 158 disconnects relays 157 and 162, thereby causing relay 173, Fig. 7, to fall back and close the circuit of release magnet 166 and restore the switch M to its normal 85 position. The relay 180, Fig. 7, is operated at the first impulse sent over the tip side of the trunk 150 and in acting opens the circuit of relay 179, and this relay acting in this manner opens the circuit of relay 180 90 itself. It will be noted that after the first impulse has been sent, relays 180 and 179 are disabled.

The operator's key-board shown in Fig. 9 consists of five rows of buttons, each row 95 having ten buttons. Number 1 button of each row is connected to a contact operated by the cam 232. Number 2 button of each row is connected to a contact operated by the cam 233. The corresponding buttons in each 100 row are connected to similar contacts. The contact controlled by the cam 232 is closed just long enough to keep relay 160, Fig. 8, energized, while one impulse is being transmitted by the commutator 242. If number 105 10 button is down, relay 160 would be closed by the cam 241 just long enough for ten impulses to be transmitted by the commutator 242. The contacts of the commutator 242 are connected directly to the normally 110 open contact of relay 160 and when this relay is energized, the impulses are connected to either the tip or sleeve side of the trunk, depending upon the position of the arm of the portion N. The buttons or keys 115 shown in these five rows, Fig. 9, are of the usual locking and indicating type. When any one button of a certain row is depressed it will release the button formerly depressed. The buttons 246, 247 and 248 are of the non-locking type.

Referring to Fig. 1^b, the wires 412 and 413 lead to the selector switch at D—D, Fig. 2^a. In order to originate a call, the operator simply throws the key 665 forward, thereby 125 connecting the retardation coil 675 and the relay 670 to the conductors 412 and 413. This originates a call and causes this trunk circuit to become connected to a key-board. When this connection is established, the op- 130

erator at the key-board sets up the call in the regular manner. When the called subscriber answers, relay 670 is energized, lighting the lamp 680, thereby indicating that 5 the called subscriber has answered. When the button 660 is pressed, the operator's telephone set is connected across the conductors 412 and 413.

Referring to Fig. 1^a, a subscriber's station 10 is shown at A² terminating in a line relay 424, which when energized lights the line lamp associated with the jack J². The answering plug P² and the calling plug P¹ are joined together for conversational purposes 15 by the conductors indicated by heavy lines. These conductors are separated by the condensers in the usual manner. The relays 416 and 417 are connected to ground and battery respectively and connected to 20 the answering plug and furnish talking current to the calling subscriber when the answering plug is placed in the jack J². The relays 410 and 415 are connected to ground and battery respectively and being connected 25 to the calling plug furnish battery and serve for controlling the supervisory lamp 411. The jack J¹ is connected to the conductors 412 and 413 when the relay 430 is energized. The action of this relay is originally 30 controlled by an operator who is provided with a key-board or key-boards for handling trunk calls from the manual to the semi-automatic exchange. This operator is provided with a button 900 and the two signal 35 lamps 414 and 420. A set of these lamps and button are individual to each trunk. The relay 430 is energized when the operator presses the button 900 and after being energized is controlled by the operator at the 40 manual exchange who inserts the plug P¹ into the jack J¹. The lamp 414 is lighted as soon as the plug P¹ is placed into the jack J¹ and notifies the semi-automatic operator 45 that the trunk she has assigned has been taken by the operator at the manual switch-board. The lamp 420 remains lighted as long as this trunk is in service and serves to notify the operator at the key-board of the busy condition of the trunks. 50 Further details in connection with the operation of the circuit herein shown will be described later.

Referring now to Fig. 2^a, the trunk conductors 412 and 413 leading from the manual exchange are connected for conversational purposes to the wipers 447 of the selector switch through the windings of the repeating coil 419 and condensers 421. The wipers 448 act as test and release wipers. 55 Relay 460 is normally connected across the answering end of the conductors in series with the resistance coil 495. This relay 460 is very sensitive and will respond to current caused by inserting the plug P¹ in the trunk 60 jack J¹. The coil 495, however, is of such

a high resistance that the relay 410, Fig. 1^a, will not pull up or even hold up through it. Relay 445 is actuated when the key-set switch picks out the trunk and in turn closes the circuit of relay 440. This latter 70 relay disconnects relay 435 which is the starting relay and corresponds to relay 21, Fig. 2. Relay 470 is the rotary repeating relay, while 455 is the test relay of the selector switch D—D. Relay 450 is connected 75 to the sleeve conductor and is of a very high resistance and is actuated when the called subscriber answers. The action of this relay shunts out the resistance coil 495, thereby causing the actuation of relay 410, Fig. 80 1^a, notifying the operator at the manual exchange or switch-board that the called subscriber has answered his telephone.

Referring to Fig. 6^a, the circuit shown is very similar to the control circuit of Fig. 6. 85 The main difference is that the time element switch X when acting instead of releasing the primary and key-set switches after a predetermined time simply removes ground from the winding of relay 130. All 90 the connections of the switch Y remain the same. When the relay 76, belonging to the time element switch X is operated, the relay 130 is deenergized. This arrangement prevents tying up the trunks from the manual 95 exchange in case several operators' calling plugs P¹ are inserted into the trunk jacks J¹ at the same time, and before these calls are connected to the key-set switches. In case several trunk calls are waiting, the relay 130 would be energized by several paths as the wire 79 is multiplied to a group of trunks and there would be no means for unlocking the relay 130 under such conditions. I have taken care of this contingency by controlling the circuits by means of the time element switch X. 100 105

Referring now to Fig. 3^a, the trunk selector switch at E—E acts in the same manner as the connector switch shown in Fig. 4, 110 in so much as it is driven in a rotary direction by predetermined impulses and in the vertical direction by predetermined impulses from the sending device. This switch is used in trunking calls from the semi-automatic exchange to the manual exchange. The semi-automatic operator receiving a call for the manual exchange presses an order wire button leading to an operator at the manual switch-board who thereupon assigns 115 a trunk. The operator at the key-board then sets up the number of the trunk assigned on her keyboard and causes the switch E—E to pick out the trunk so assigned. 120

Relays 505 and 510 are the repeating relays 125 and respond to impulses from the sending device. Relay 540 is energized by the first selector switch when an idle trunk selector is picked out. Relay 515 is the control relay and is energized by the action of the vertical 130

relay 510 and is deenergized by the action of the rotary relay 505. The retardation coil 520 and relay 525 are connected to ground and battery respectively and serve to operate signals in connection with the trunk shown in Fig. 4^a.

Referring to Fig. 4^a the trunk conductors leading from the semi-automatic exchange are separated from the plug P⁴ by means of 10 the repeating coil and condensers as shown. Relay 570 is the signal relay and is energized when the trunk is picked out by the trunk selector. Relays 575 and 580 are connected respectively to battery and ground 15 and furnish talking current to the called subscriber. Relay 585 is the ringing relay and when actuated severs the cord or trunk circuit and connects generator current to the called line. Relay 590 is energized by 20 the tip relay 580 when the called subscriber answers and prevents any flashing of the lamp 582.

The subscriber's line circuit and equipment as shown is the same as in Fig. 1^a.

25 In describing the operation of my system, I will first trace a connection from a calling subscriber in the semi-automatic exchange to another subscriber in the same exchange. For this combination I will use Figs. 1, 2, 30 3, 4, 5, 6, 7, 8 and 9, arranged as shown in Fig. 10. The equipment which is located at the semi-automatic exchange is represented by the Figs. 1 to 7 inclusive, while that portion located at the manual exchange 35 or at a distant point is represented by Figs. 8 and 9.

The subscriber at station A removing his receiver closes the circuit of the line relay 2 in series with the group relay 3. This latter 40 relay operating closes the circuit of the master relay 4, which in turn completes the connection of the stepping magnet 7 through the contacts of relay 5. This magnet operating closes the circuit of relay 6, which in 45 turn opens the circuit of the magnet itself, thereby causing the switch W to vibrate and step its wipers around over the contacts. This switch will continue to rotate until an idle primary switch as shown in Fig. 2 is 50 found. As soon as such a switch is found, the relay 5 is placed in series with relay 21, Fig. 2 as follows: ground, contact of relay 4, 5, 18, upper bank of switch W, 14, 21, 70 to battery B through the contacts of relay 55 24. Relay 5 becoming active opens the circuit of the stepping magnet 7 bringing the switch W to rest on contacts leading to the idle primary switch. Relay 21 operating 60 closes the circuit of the rotary magnet 31 of the primary switch as follows: battery B, contacts of relay 21, 80, back contact of relay 24, 71, contacts of relay 28, contacts of relay 22, rotary magnet 31, to ground. The operation of magnet 31 causes the primary switch 65 C to rotate until the wiper 64 reaches the

contact rendered busy by the energizing of relay 3 which connects grounded battery to this contact.

The wiper 64 is carried on the same spindle with wipers 63 and 65 and while the 70 switch is rotating, the wiper 64 passes over the row contacts. There are ten of these contacts to each primary switch as the lines are divided into ten groups. There are also 75 ten sets of individual contacts arranged in vertical rows, one row associated with each contact and which the wipers 63 and 65 respectively engage. It follows that after the switch picks out the group in which a line is calling it will afterward step vertically until so the wipers engage the individual contacts leading to the calling line.

As soon as a row contact is found, the circuit of relay 22 is closed as follows: battery B, contacts of relay 21, 80, back contacts of 85 relay 24, 71, 22, 64, 13, to ground through the contact of relay 3. Relay 22 operating disconnects the rotary magnet 31 and in its place connects the vertical magnet 30, thereby causing the switch to step vertically until 90 the busy individual test contact is found, thereby closing the circuit of relay 24 as follows: battery B, 24, 68, contacts of relay 22, 66, 67, 65, 11, contacts of relay 2 to ground through the contacts of relay 1. Relay 24 operating disconnects relay 22, which in falling back disconnects relay 24 from the wiper 65 and connects it instead to the sleeve wiper 63 attached to the trunk conductor 51. The foregoing action places relay 24 in series with the cut-off relay 1. The action of the latter relay disconnects the line and group relays. The operating of relay 24 partially opens the circuit of relay 21, but the circuit of this relay is maintained 105 through the contacts of relay 25. Battery for talking purposes is now supplied to the calling subscriber through relays 23 and 24.

Relay 21 remains energized until the primary switch finds the calling line and until 110 the key-set switch finds the calling trunk. This relay when first actuated connects battery to the common starting wire 79 leading to relay 130 and also places battery to wire 62 leading to the individual test contact of 115 the key-set switch, Fig. 7.

Relay 130, Fig. 6, operating closes the circuit of the stepping magnet 133 of the switch Y causing this switch to rotate in search of an idle key-set switch such as shown in 120 Fig. 7. When such a switch is found, relay 131 is placed in series with relay 152, Fig. 7, as follows: ground contacts of relay 130, 131, 138 through the upper bank contacts of switch Y, 140, 152, 195, cam springs 196, 125 to battery B. This circuit passes through the contacts of the special control relay 700. Relay 131 acting closes the circuit of relay 132, which when energized places ground on the wire 138 and shunts out relay 131. This 130

direct ground is also connected to the wire 140 which is multiplied to other Y switches and renders the contacts busy. The operating of relay 132 also connects ground to the

5 row contact of the key-set switch as follows: ground, middle bank of contacts of the switch Y, 141 to the row contact, Fig. 7.

The operating of relay 152 places ground to the rotary magnet 165 through the contacts of relays 153 and 163. Relay 163, the interrupter relay for the magnets is caused to vibrate by this. The switch M will continue to rotate until the row contact is found, whereupon the circuit of relay 153 is 15 closed by ground being placed on the row contact as previously traced. The action of the key-set switch M is identical with that of the primary switch, Fig. 2. Relay 153 operating disconnects the rotary magnet 165 20 and in its place connects the vertical magnet 164, thereby causing the key-set switch to step vertically until the individual test contact which is connected to battery through the contacts of relay 21, Fig. 2, 25 is found. As soon as this contact is found, the circuit of relay 154 is closed and upon operating disconnects relay 152, which in turn disconnects relay 153 and causes the wipers of switch M to rest on contacts leading to the primary trunk, Fig. 2. As soon as relay 152 falls back, the circuit of relay 190 is closed as follows: ground, contacts of relay 152, 190, release magnet 166, 209, cam springs 196 to battery B. Relay 190 becomes energized but is of a high resistance and does not affect the magnet 166. The action of this relay closes the circuit of relay 173 as follows: battery B, 213, 173, 214 to ground through the contacts of relay 154.

40 The energizing of relay 173 closes the circuit of relay 25, Fig. 2, as follows: ground, contact of relay 152, contacts of relay 173, 170, 169, 59, 25 to battery B. Relay 25 acting disconnects relay 21, thereby removing 45 battery from the individual test contact of the switch M, Fig. 7, and releases relay 154. Relay 154 falling back completes the circuit of relays 173, Fig. 7, and 156, Fig. 8, as follows: battery B, contacts of relay 190, 213, 50 173, 214, contacts of relay 154, 175, 156, 217, contacts of relay 155, 202, contacts of relay 157, 218, contacts of relay 158 to ground. As soon as relay 153 becomes energized upon 55 finding the row contact, it completes the circuit of relay 179. Relay 179 is now controlled by the action of relay 180.

As soon as relay 21, Fig. 2, becomes disconnected relay 130, Fig. 6, and relay 132 are released and the switch Y is free to handle 60 other calls.

We now have relays 23 and 24, Fig. 2, energized and relays 190, 179 and 173, Fig. 7, energized and also relay 156 in Fig. 8. The energizing of relay 156 completes the circuit of the two signal lamps 243 and 244,

Fig. 9, notifying the operator at the distant exchange of a call in the semi-automatic exchange.

In the present system I have provided ten primary switches such as shown in Fig. 2 for each group of one hundred lines. Each group of ten primary switches are provided with a switch Y for picking out idle key-sets. The wire 141 leading from the Y switch to the row contact of the key-set 70 switch is not multiplied. As soon as the Y- switch picks out an idle key set switch, ground is placed on the row contact of that switch only, thus preventing interference, as no key set switch will have more than one 75 row contact grounded at any instant.

The operator noticing the lighting of the two lamps 243 and 244 presses the answering button 248 operating relay 155, thereby connecting her telephone set across the tip and 80 sleeve conductors of the trunk. The action of this relay disconnects relay 156, thereby deenergizing relay 173, Fig. 7. This latter relay falling back removes ground from the wire 170 leading to the wiper 169, thereby 85 releasing relay 25, Fig. 2. Relay 25 falling back closes the tip and sleeve trunk conductors and enables the operator at the distant exchange to converse with the calling subscriber.

95 Each operator is provided preferably with three sets of keys such as shown in Fig. 9, thus enabling her to handle calls without loss of time, for while a call is going through on one key-board, she can receive calls on the other two.

The cams of the sending device shown at 230 to 241 inclusive may be common to a group of key-sets. The commutator 242, however, is preferably individual to one key-set or to one operator.

In the present instance I have shown the exchange to be of ten thousand lines capacity, and in case of larger exchanges it will be necessary to add additional rows of buttons to the operator's key-board and to insert additional selector switches.

110 The operator after getting the proper number from the calling subscriber presses one button in each row corresponding to the desired number. The starting button 247 is then pressed closing the circuit of relay 157 as follows: ground, 247, 186, 157, 162 to battery B. The operating of relay 157 disconnects relay 155 and causes the guard 115 lamp 244 to light. The action of this relay also connects the starting wire 189 to the stepping magnet 161. Relay 162 operating connects ground to the wire 175, thereby again energizing relay 173. The energizing 120 of relay 173 again completes the circuit of relay 25, Fig. 2, the action of which severs the tip and sleeve conductors.

125 As soon as the cam 231 of the sending device, Fig. 9, closes the contacts associated 130

with it, the circuit of the stepping magnet 161 is closed, thereby causing the shifting switch, Fig. 8, to take one step and connect the impulse wire 191, to the tip side of the trunk 150 through the contacts of relay 160 when this latter relay is energized. If number 9 button, row R, is pressed, this relay will be held energized by the operation of the cam 240 until nine impulses have been transmitted by the commutator 242. These impulses operate the rotary relay 29, Fig. 2, as follows: ground, 242, 191, contacts of relay 160, 198 through the portion N of the shifting switch, 150, 167, 60, 54, cam springs 40, 29, 42, to battery B through the contacts of relay 25. Relay 29 responding to these impulses closes the circuit of the rotary magnet 34 causing the first selector switch D to rotate and come opposite the ninth row of contacts. As soon as the contact springs operated by the rotary magnet 34 are closed, ground is at once placed between the winding of relay 29 and the coil 42 thus shunting and regulating the relay. As soon as the magnet finishes its stroke the relay is shunted out, thereby removing battery from the magnet itself.

After these rotary impulses have been sent, the starting cam 231 causes the shifting switch to take another step, thereby connecting the impulse circuit to the sleeve conductor 151. The relay 160 is held energized by the action of the cam 230 until a single impulse is transmitted. This impulse operates relay 27, Fig. 2, as follows: ground, 242, 191, contacts of relay 160, 198, N, 151, 167, 61, cam springs 40, relay 27 to battery B through the contacts of relay 25. Relay 27 after receiving this impulse is held energized by the following path: battery B, contacts of relay 25, locking contacts of relay 27, 72 to ground through the contacts of relay 28. The cam springs 41 are operated at the first rotary motion of the switch D while the cam springs 40 are operated at the first vertical motion of the switch D, and the operating of this latter set disconnects relays 27 and 29 from the tip and sleeve conductors. The operating of relay 27 closes the circuit of the vertical magnet 33 as follows: battery B, contacts of relay 28, 71, contacts of relay 27, 33 to ground. This magnet in operating closes the circuit of relay 28, which in turn opens the circuit of the magnet itself. The action thus set up causes the magnet to vibrate and to step the switch D vertically. When the circuit of relay 28 is closed by the action of the magnet 33 closing its contacts, the circuit of relay 27 is partially opened, but it will remain energized so long as the test wiper 57 is passing over busy or ground contacts. If, while the relay 28 is energized, the wiper 57 comes to rest on an idle contact, then the relay 27 will at once be-

come deenergized and disconnect the vertical magnet 33. The controlling of the test relay 27 in this manner insures a full step of the magnet 33 as the wiper 57 fully engages the test contacts before the relay 27 is opened by the action of relay 28.

At the third rotation of the sending device impulses corresponding to the hundreds are sent over the tip side of the trunk to the second selector, Fig. 3, thereby operating relay 81. This relay is connected to the tip side of the trunk 90 through the cam springs 88. The action of this relay closes the circuit of the rotary magnet 85, causing the switch E to rotate and come opposite a row of contacts leading to connector switches.

At the fourth rotation of the sending device a single test impulse is sent over the sleeve side of the trunk operating relay 83. This relay closes the circuit of the vertical magnet 84 causing the switch E to step vertically until the test wiper 102 comes to rest on contacts leading to an idle connector switch. This test relay is controlled in the same manner as relay 27, Fig. 2, and the rotary relay and rotary magnet are controlled and regulated in the same manner as the rotary magnet and rotary relay in Fig. 2. At the first vertical step of the switch E, the cam springs 88 are opened, thereby disconnecting relays 81 and 83 respectively from the tip and sleeve conductors. Relay 80 becomes energized by ground being connected to the test wiper 57 through the contacts of relay 28, Fig. 2, thereby opening the circuit of the release magnet 93.

At the fifth rotation of the sending device impulses corresponding to the button depressed in the row V Fig. 9, are sent over the tip side of the trunk operating relay 310 of the connector switch, Fig. 4. The action of this relay closes the circuit of the stepping magnet 360 of the party line distributing switch as follows: ground, contacts of relay 310, 321, contacts of relay 330, 323, 360, 318, to battery B through the contacts of relay 320. The shifting switch F takes a number of steps corresponding to the impulses designated by the button in the row V, Fig. 9. The action of relay 310 also closes the circuit of relay 315 as follows: battery B, 319, 315, contacts of relay 315, 306, 102, 89 to ground through the contacts of relay 82, Fig. 3.

At the sixth rotation of the sending device impulses corresponding to the button pressed in the row T are sent over the sleeve side of the trunk operating relay 305. The action of this relay closes the circuit of the rotary magnet 355 as follows: ground, contacts of relay 305, 314, cam springs 380, 316, 355 to battery B. This magnet operating causes the connector switch G to rotate and bring its wipers opposite a group of contacts lead-

ing to the desired line. The action of relay 305 also closes the circuit of relay 330, thereby disconnecting the magnet 360 and in its place connecting the vertical magnet 350. At the seventh rotation of the sending device impulses are sent over the tip side of the trunk corresponding to the button pressed in the row U, thereby operating relay 310 a second time. This relay now operating closes the circuit of the vertical magnet 350 causing the switch G to step vertically and bring its wipers 390 into engagement with contacts leading to the desired line. When the switch G takes its first vertical step, the cam springs 380 are operated disconnecting the rotary magnet 355. At the eighth rotation of the sending device a single test impulse is sent over the sleeve side of the trunk, operating relay 305 a second time. This relay acting at this time connects the test relay 345 directly to the sleeve conductor 303 leading to the wiper 390. If the called line is busy, relay 345 will at once become energized and lock itself to ground over the test wire 306. The action of this relay connects a suitable tone test to the conductor 301 and also closes the circuit of the release magnet 365, restoring the switch G to its normal position. If the called line is not busy, the relay 345 will not be affected. The action of relay 305 opens the circuit of relay 315, thereby connecting relays 320 and 325 to the tip and sleeve sides of the wipers 390. Relay 325 is placed in series with the cut-off relay of the called line. As soon as relay 325 is operated, the circuit of the ringing relay 340 is completed by means of the commutator 370. The action of the ringing relay disconnects the tip relay 320 and connects generator current of the desired frequency or character to the called line. As soon as the ringing relay is energized, the resistance coil 385 is connected from battery B to the sleeve conductor 303. This resistance coil can be of a very low resistance so as to shunt the sleeve relay 325 so as to open the sleeve side of the trunk when necessary. The circuit of relay 340 is maintained after relay 325 is deenergized in the following manner: ground, commutator 370, 340, contacts of 340, 324, contacts of relay 330, contacts of relay 315, 321, contacts of relay 330, 322, 350 to battery B. The circuit of the cut-off relay of the called line is kept closed by battery through the resistance coil 395 after relay 325 falls back.

At the next rotation of the sending device the circuit of relay 158, Fig. 8, is connected to battery through the portion P of the shifting switch. The action of this relay disconnects the relays 157 and 162. The action of relay 162 removes ground from the wire 175, thereby releasing relay 173, Fig. 7. When the first rotary impulse is sent over

the conductor 150 the relay 180 was affected 65 and thereby unlocked the relay 179. Relay 173 falling back in the manner just explained allows the circuit of the release magnet 166 of the switch M to be completed as follows: battery B, cam springs 196, 209, 70 166, contacts of relay 179, 193, contacts of relay 173 to ground through the contacts of relay 152. The action of this magnet restores the switch M to its normal position. The relay 158, Fig. 8, will continue to remain energized and complete the circuit of the stepping magnet 161 until the wiper of the portion P of the shifting switch reaches its normal or resting position. The circuits and apparatus shown in Figs. 7 and 8 are 80 now restored to their normal position and are ready to be used for other calls. Referring to Fig. 4, relay 320 is energized when the called subscriber answers and when actuated releases relay 330. The action of 85 this relay 330 disconnects the ringing relay 340 and the calling and called subscribers are connected as indicated by the heavy lines throughout the various figures.

When the called subscriber hangs up his 90 receiver the connector switch G is restored in the following manner: The relay 320 falling back closes the circuit of the stepping magnet 360 as follows: ground, commutator 353, I, 398, contacts of relay 330, 95 contacts of relay 315, 321, contacts of relay 330, 323, 360, 318 to battery B through the contacts of relay 320. The magnet 360 will continue to vibrate until the wiper of the portion I reaches its normal or resting position. Just before this position is reached, however, the wiper at H closes the circuit of the release magnet 365 as follows: battery B, 365, 332, H, 327, contacts of relay 315 100 to ground through the contacts of relay 305. The action of the magnet 365 restores the switch G to its normal position.

The calling subscriber upon hanging up his receiver causes the tip relay 23, Fig. 2, to fall back, thereby closing the circuit of the release magnet 32 of the primary switch C and the release magnet 35 of the first selector switch D. The circuit of these magnets is closed as follows: ground, 32, 260, 110 contacts of relay 23, 73, 35, cam springs 41, contacts of relay 21, 69 to battery B through the contacts of relay 25. Magnet 32 operating releases the primary switch C while the magnet 35 releases the first selector switch D. As soon as the first selector switch wiper 57 leaves the test contact relay 80, Fig. 3, becomes deenergized, thereby closing the circuit of the release magnet 93 as follows: battery B, contacts of relay 80, 93, 100, cam springs 87 to ground. The action of this magnet restores the switch E to its normal position.

In case the called for party does not an-

swer, then the calling subscriber effects the release of the connector switch as well. This release is brought about when the second selector switch wipers leave the contacts of the connector switch, thereby removing ground from the test wire 306. Should ground be removed in this manner and release relays 315 and 330 the circuit of the magnet 360 is closed in the same manner as though the called subscriber had answered and then hung up his receiver. The action of the switch 1 closes the circuit of the magnet 365 in restoring.

I will now trace a connection when a subscriber in the manual exchange desires to converse with a subscriber in the semi-automatic exchange. The circuits used are arranged as shown in Fig. 11. The apparatus shown in Fig. 1^a with the exception of the two lamps 414 and 420 and the button 900 are located at the manual switch-board or exchange. The button and lamps are located before the operator who handles the calls from the semi-automatic exchange. The button and lamps are arranged in a suitable manner in connection with her key-board.

We will suppose for instance that the subscriber A² desires to converse with the subscriber A⁵ whose line is connected to the semi-automatic exchange. The subscriber at A² removing his receiver closes the circuit of the relay 424 lighting the lamp associated with the jack J². The operator at the manual board places the plug P² into the jack J² and inquires for the number, and learning that the call is for the semi-automatic exchange presses an order wire button leading to the operator at the key-board. As shown, the order button wires can be of any suitable type. By pressing the order wire button she is able to converse with the operator at the key-board who thereupon assigns an idle trunk and at the same time sets up the number of the desired party on her key-board. The operator at the manual board then places the calling plug P¹ into the jack J¹, thereby placing relays 415 and 425 in series. The action of relay 415 lights the lamp 411 through the contacts of relay 410. The action of relay 425 closes the circuits of the lamps 420 and 414, the latter through the contacts of relay 430. The lighting of these lamps notifies the operator at the key-board that the trunk assigned has been taken by the manual operator. This former operator presses the button 900 energizing relay 430. This latter relay after once energized has its circuit maintained through the contacts of relay 425 and when so operated connects the tip and sleeve conductors 412 and 413 respectively to the trunk jack J¹. The operator at the key-board in addition to pressing this button also presses a control button 705, Fig. 8,

which closes the circuit of relay 700, Fig. 7, thereby opening the starting circuit for relay 152. This relay 700 instead of being provided with normally closed contacts can be provided with normally open contacts which are closed when the button 705 is operated. The operator who handles these incoming calls from the manual exchange can be provided with any number of key-sets and by manipulating the button 705 can put any one of them into service at the proper time. In case one operator should handle regular calls as well as these trunk calls she would be provided with a certain number of key-set switches or key-boards serving a group of trunks such as shown in Fig. 2^a and with other key-set switches for serving a group of trunks such as shown in Fig. 2.

After setting up the number on the key-board which she desires to use and after pressing buttons 900 and 705, the call is connected to the key-board in the following manner: The pressing of button 900 after closing the trunk wires causes relay 460, Fig. 2^a to become energized by current supplied through the relays 415 and 410, Fig. 1^a. The action of this relay closes the circuit of relay 435 as follows: ground, contacts of relay 460, 434, cam springs 441, 432, contacts of relay 440, 433, 435 to battery B. The action of this relay 435 places battery 95 on the common starting wire 79 and also to the individual test contact on the key-set switch, Fig. 7. Battery being placed on the wire 79 energizes relay 130, Fig. 6^a causing the switch Y to rotate in search of an idle 100 key-set switch. The only idle switch serving this group of trunks is that rendered so by the operator pressing button 705, and it therefore follows that this will be the key-set picked out. When this key-set switch, 105 Fig. 7, is found, a relay 445 is operated in the same manner as relay 25, Fig. 2. The action of the key-set switch in picking out an idle trunk is identical with that in picking out a primary trunk shown in Fig. 2. 110 The action of relay 445 closes the circuit of relay 440 as follows: battery B, contacts of relay 445, 431, 440, 434 to ground through the contacts of relay 460. The action of relay 440 disconnects relay 435, which in 115 turn opens the circuit of relay 130, Fig. 6^a.

The operator at the key-board receives the signals as in regular calls and presses the starting button in the regular manner. The action of the sending device and relays of 120 the key-set switch is identical with that as already described in tracing a connection from a subscriber in the semi-automatic exchange to a subscriber in the same exchange.

The first set of impulses are sent over the 125 tip side of the trunk operating the rotary relay 470, which in turn closes the circuit of the rotary magnet 475 causing the switch

to rotate and come opposite a row of contacts leading to the second selector switches. At the second rotation of the sending device a single test impulse is sent over the sleeve side of the trunk operating relay 455. This relay in acting closes the circuit of the vertical magnet 480 and maintains the circuit closed until an idle second selector is picked out, whereupon the test relay 455 drops back. At the first vertical step of the switch, cam springs 442 are operated, thereby disconnecting the relays 455 and 470.

The balance of the impulses go forward and operate the second selector and connector switches in the same manner as previously described. After the connection is entirely built up, the key-set switch, Fig. 7, restores and the subscriber at the manual exchange is connected with the subscriber at the semi-automatic exchange. Relay 450 is of a very high resistance and is placed in multiple with the tip relay 320 of the connector. This relay is actuated when the called subscriber answers and short circuits the resistance coil 495, thereby allowing the relay 410, Fig. 1^a to become energized and extinguish the lamp 411. The operator at the manual exchange getting this signal knows that the subscriber at the semi-automatic exchange has answered.

The lamp 420 before the operator at the key-board remains lighted so long as the operator at the manual board has the plug P¹ in the jack J¹ and serves as a busy signal. In assigning trunks, the operator at the key-board will designate one at which no lamps are lighted. The operator at the key-board has no control over the connection after it is once established as the control after being established is by the operator at the manual board.

At the end of the conversation the called subscriber upon hanging up his receiver releases the connector switch G, Fig. 4 in the manner already described. As soon as this switch restores, however, the relay 450, Fig. 2^a, becomes deenergized and removes the shunt from the coil 495. As soon as this shunt is removed, relay 410, Fig. 1^a, falls back, lights the lamp 411 and notifies the operator at the manual exchange that the called party has hung up his receiver. The calling subscriber upon hanging up his receiver deenergizes relay 416, thereby lighting the lamp 428. The operator upon getting these two signals withdraws the plugs P² and P¹ respectively from the jacks J² and J¹. When the plug P¹ is withdrawn, relay 425 drops back, deenergizes relay 430 and extinguishes lamp 420. When the plug P¹ is withdrawn, the relay 460 has its circuit broken and falling back unlocks relay 440. This latter relay in falling back closes the circuit of release magnet 485 as follows:

battery B, contacts of relay 445, 427, contacts of relay 440, 485, lower wipers 448 which are short circuited by the test contacts 429 to ground through the contacts of relay 465. The action of the release magnet restores the switch D—D to its normal position. The releasing of the switch D—D removes ground from relay 80, Fig. 3, the action of which closes the circuit of the release magnet 93 restoring the second selector switch E to its normal position.

When a subscriber in the semi-automatic exchange desires to converse with a subscriber of the manual exchange the circuits are arranged as shown in Fig. 12. The apparatus shown in Figs. 1, 2, 3^a, 6 and 7 is located at the semi-automatic exchange. The apparatus shown in Figs. 8 and 9 is located at the exchange at a distant point. The apparatus shown in Fig. 4^a is located at a manual switch-board. The bank contacts shown schematically, however, are, of course, located before the trunk selector switch of the semi-automatic exchange. The subscriber A of the semi-automatic exchange desiring to converse with a subscriber at the manual exchange removes his receiver and becomes connected to an idle operator's keyboard in the manner previously described in tracing a call from the subscriber in the semi-automatic exchange to another subscriber in the semi-automatic exchange.

The operator, however, instead of pressing the regular starting button 247 presses a special starting button 246, thereby closing the circuit of relay 159 as follows: ground, contacts of 246, 184, 159 to battery B. The action of relay 159 and the button 246 closes the circuit of relays 157 and 162 as follows: ground, contacts of 246, 184, contacts of 159, 186, 157, 162 to battery B. The energizing of relays 157 and 162 perform the same functions as previously described. The action of relay 159 removes battery from the first five contacts of the portion P of the shifting switch but connects battery to the next three contacts. It will be noted that when relays 157 and 162 are alone actuated battery is removed from the first eight contacts of the portion P, but when the relay 159 is also actuated battery is only removed from the first five contacts. This arrangement limits the travel of the shifting switch to five rotations of the sending device, for at the sixth rotation the relay 158 encounters battery through the portion P of the shifting switch. In trunking from a semi-automatic to the manual exchange it is only necessary to operate the first selector switch and then the trunk selector switch, thereby cutting out three rotations of the sending device for in regular calls eight rotations are required for operating the various switches. The operation of relay 159 also

disconnects the test impulse wire 203 from the fourth contact of the portion O and in its place connects the common wire 206 belonging to the strip of buttons T, Fig. 9. 5 The shifting of the circuits in this manner allows the impulses to be transmitted in the following order: At the first rotation of the sending device impulses from the strip R are sent over the tip side of the trunk and 10 at the second rotation a single test impulse is sent over the sleeve side of the trunk. At the third rotation of the sending device impulses from the strip S are sent over the tip side of the trunk and at the fourth rotation impulses from the strip T are sent over the sleeve side of the trunk and at the 15 fifth rotation impulses from the strip V are sent over the tip side of the trunk.

The operator of the semi-automatic exchange upon receiving a call for a subscriber at the manual exchange presses her order wire button leading to the operator at the manual switch-board, who assigns an idle trunk to be used. The operator of the semi-automatic exchange sets up the number of the trunk assigned on the buttons R, S and T. After pressing a special trunk button the impulses corresponding to the button pressed in the strip R operate rotary relay 20 29, Fig. 2, as previously described causing the switch D to rotate and come opposite a group of trunks leading to trunk selector switches. At the next rotation of the sending device a single test impulse operates relay 24 27, Fig. 2, causing the switch D to step vertically and pick out an idle trunk selector such as shown in Fig. 3^a. As soon as this trunk selector is picked out relay 540 becomes energized and connects ground to one 40 terminal of relay 515. At the third rotation of the sending device impulses corresponding to the button pressed in the strip S are sent over the tip side of the trunk operating relay 505. The action of this relay 45 closes the circuit of the rotary magnet 530 as follows: battery B, contacts of relay 505, 509, 530, 512 to ground through the cam springs 522. The action of this magnet connects ground by means of its contact springs 50 to the wire 516, thereby regulating the action of relay 505. At the fourth rotation of the sending device impulses corresponding to the button pressed in the strip T are sent over the sleeve side of the trunk operating relay 510. The operation of this relay 55 closes the circuit of the vertical magnet 535 causing the switch E—E to step vertically and bring its wipers 550 to rest on contacts leading to the trunk assigned. The 60 action of relay 510 also closes the circuit of the locking relay 515, thereby disconnecting battery from the winding of relay 525 and ground from the retardation coil 520. At the fifth rotation of the sending device 65 impulses corresponding to any button pressed

in the row V are sent over the tip side of the trunk, again causing the actuation of relay 505. The action of this relay simply unlocks the relay 515, thereby connecting the relay 525 and the retardation coil 520 across 70 the tip and sleeve side of the wipers 550.

At the sixth rotation of the sending device the relay 158 has its circuit closed to battery as follows: ground, 158, 187, P, 199, contacts of relay 159 to battery B. The action of this relay 158 causes the switch M, Fig. 7, to restore to its normal position in the manner previously described.

The calling subscriber at the manual exchange is now connected to the trunk at the 80 manual exchange. The wipers 550 of the switch E—E, Fig. 3^a, coming in connection with contacts leading to a trunk at the manual switch-board energizes relay 570, Fig. 4^a. This relay is very sensitive and is connected 85 to the conductors 552 and 551 through the resistance coil 566 and the windings of the repeating coil 572. This relay 570 is energized by current through the windings of the relay 525 and the retardation coil 520. 90 The coil 566 is of such a high resistance that the relay 525 will not operate through it. The action of relay 570 closes the circuit of the signal lamp 581 as follows: battery B—B, contacts of relay 570, 567, contacts of 95 relay 575, 581 to ground. The lighting of this lamp notifies the operator at the manual switch-board that the trunk she has assigned to the operator of the semi-automatic exchange has been picked out and she 100 thereupon places the plug P⁴ into the jack J⁴ of the wanted line. As soon as this plug is inserted the relay 575 is placed in series with the cut-off relay 584. The energizing 105 of relay 584 disconnects the line relay 586 and connects the line terminals to the jack J⁴. The energizing of relay 575 extinguishes the lamp 581 but closes the circuit of the supervisory lamp 582 through the contacts of the relay 590. The tip relay 580 110 is connected to the conductor 553 by the action of relay 575. The operator after placing the plug P⁴ in the jack J⁴ presses the ringing key 555, thereby closing the circuit of the ringing relay 585 as follows: ground, 115 resistance coil 565, 585, 567 to battery B—B, through the contacts of relay 570. The energizing of the ringing relay 585 connects generator current to the called line. When the called subscriber answers his telephone, the 120 tip relay 580 is energized, thereby closing the circuit of the locking relay 590. The energizing of this relay 590 extinguishes the lamp 582. The action of relay 580 also 125 short circuits the resistance coil 566, thereby allowing the relay 525, Fig. 3^a, to become energized and close the trunk conductors for conversational purposes.

When the calling subscriber at the semi-automatic exchange hangs up his receiver he 130

releases the primary and first selector switch, Fig. 2, in the same manner as previously described. The releasing of the first selector switch D removes ground from the test wire 503, Fig. 3^a, thereby deenergizing relay 540. The deenergizing of this relay closes the circuit of the release magnet 545 as follows: ground, contacts of relay 540, 504, 545, 506, cam springs 521 to battery B. The action 5 of this magnet restores the switch E—E to its normal position. When this switch restores, the relay 570, Fig. 4^a, is deenergized and again closes the circuit of the signal lamp 581 as follows: battery B—B, contacts 10 of 570, 569, contacts of relay 575, 581 to ground. The operator at the manual switch-board upon getting this disconnect signal removes the plug P⁴ from the jack J⁴, thereby 15 restoring all the parts to their normal positions.

In originating calls at the semi-automatic exchange for the purpose of giving special service such as for reverting calls, etc., the various figures are arranged as shown in 25 Fig. 13.

The apparatus shown in Figs. 2^a, 3, 4, 5, 6^a and 7 is located at the semi-automatic exchange, while the apparatus shown in Figs. 1^b, 8 and 9 are located at a distant point. 30 The apparatus shown in Fig. 1^b is located before an operator who is provided with a key-board arranged for handling calls in the same manner as trunk calls from the manual to the semi-automatic exchange.

35 In order to originate a call the operator presses the button 665, thereby connecting battery to the tip and sleeve conductors 412 and 413 through the retardation coil 675 and relay 670. Battery being placed on the 40 trunk conductors in this manner affects the trunk circuit, Fig. 2^a, in the same manner as though an operator at the manual switch-board had placed a plug into the trunk jack as has been already described. The operator 45 of the semi-automatic exchange presses the button 705, Fig. 8, thereby energizing relay 700, Fig. 7, so as to render the switch M operative in response to the originated call.

This trunk is connected to the key-board 50 in the same manner as previously described in connection with a trunk call from the manual exchange and the various selector and connector switches are controlled in the same manner. When the called subscriber 55 removes his receiver, the relay 450, Fig. 2^a, is energized, short circuits the resistance coil 495 and allows relay 670, Fig. 1^b, to become energized. The action of this relay lights the lamp 680. The operator noticing this 60 signal presses the button 660, thereby connecting her telephone set to the trunk conductors 412 and 413 allowing her to converse with the called subscriber. After the connection is built up to the called line, the key-set switch, Fig. 7, and all the apparatus

shown in Fig. 8, are restored to their normal position. After the operator is through conversing with the called party she restores the button 665, thereby removing the relay 670 and the coil 675 from the trunk conductors 412 and 413. Relay 460, Fig. 2^a, is then deenergized and falling back closes the circuit of the release magnet 485 restoring the switch D—D to its normal position. The restoring of the switch D—D also causes the 75 second selector switch, Fig. 3, to restore. When the called subscriber hangs up his receiver he releases the connector switch in the regular manner.

In case a subscriber at the semi-automatic 80 exchange after becoming connected to the key-board notifies the operator that he wishes to converse with a party on his own line, the call is handled as follows: The operator notifies the subscriber to hang up 85 his receiver and then presses the starting button causing the release of the primary switch and also the key-set switch. She then operates the special circuit shown in Fig. 1^b and brings a call in on one of her key-sets. 90 After receiving the call that she herself has originated she sets up the number of the party desired on the line and puts a call through in the regular manner. The operator has previously notified the calling subscriber to wait for thirty seconds or so in order to give her time to call the party on his line. After the connection is built up 95 and the key-set switch restores, the operator still has supervision and control over 100 the connection by means of the circuits shown in Fig. 1^b. When either party on the line removes his receiver, the relay 670 is energized and the lighting of the lamp 680 notifies the operator of the fact. She can 105 then press the button 660 and find out whether the parties are conversing, and if so, she releases the special selector and also the second selector switch.

In Fig. 3 I have shown an extra row of 110 bank contacts at 901 and 905. These contacts are not tied together as the regular contacts are as shown by the wire 96. In connection with Fig. 2^a it will be noted that the wipers 448 are not tied together but that the 115 testing is done through one wiper while the release magnet 485 is connected to the other. In regular connections the test banks are connected together as shown by the wire 96, but an extra set of contacts is provided in the 120 bank so as to prevent the release of certain calls. This row of contacts may be located at any position in the bank but is preferably the last row. The operator of the semi-automatic exchange receiving a call from an 125 annoying subscriber can set up a number on her key-board which will drive the switch D—D to the special row of contacts and then cause the switch to pick out an idle one of the special contacts. It will be noted 130

that when the wipers 448 engage any one of these contacts in the special row that the circuit of the release magnet 485 is kept open. The lamp 910 can be located at the wire chief's desk or any suitable place so that for such calls a signal will be given and the attendant or wire chief can trace the connection back to where it originated.

I have not shown this method of releasing 10 the switches D and E, but it can be so added if desired.

It will be noted that I have described the operators of the semi-automatic exchange as being located in the same exchange with a 15 manual switchboard. It of course follows that these operators can be located in a separate exchange without changing the circuits or manner of operating them. It is common practice to extend order wires 20 between exchanges, and the wires leading to the lamps 420 and 414 as well as to the button 900 can be extended.

When the distance is very great relays can be inserted in place of the lamps and when 25 actuated light the lamps on a local circuit.

By allowing the subscriber to repeat or give the number over again in certain instances, the order wires can be dispensed with. Under these operating conditions the 30 lamps 420, 414 and the button 900 Fig. 1^a can be dispensed with. The relay 430 can be operated directly by the contact on relay 425 which now closes the lamp circuits. The operator at the manual exchange in 35 calling the semi-automatic exchange tests for an idle trunk jack in the regular manner.

The insertion of the plug causes the trunk Fig. 2^a, to be picked out by an idle key-set switch without the coöperation of the operator of the semi-automatic exchange.

The special button for closing the circuit of the starting relay 152, Fig. 7, is not needed.

The subscriber at the manual exchange 45 can give his number to the second operator namely, the operator at the key-board who thereupon causes the call to be completed by means of her key-board and sending device.

Having described my invention what I 50 claim and desire to secure by Letters Patent is:

1. In a telephone exchange system, the combination of a calling subscriber's line, a 55 called subscriber's line, a link circuit and automatic switching mechanism for interconnecting said lines, an operator's position including means for directing the action of said switching mechanism, a trunk line 60 leading to said operator's position, an interposed automatic switch for connecting the operator's position with said link circuit, said interposed automatic switch being connected with the operator's position over 65 the trunk line, said trunk line consisting

only of a pair of conductors over which the action of the automatic switching mechanism is directed and of a separate conductor over which the signaling and release is controlled.

2. In a telephone exchange system, the combination of a calling subscriber's line, a called subscriber's line, means for interconnecting the lines including automatic switching mechanism in which said lines 70 terminate, an operator's key set, an automatic key set switch associated therewith adapted to connect the subscribers' lines for control of the automatic switching mechanism by the key set, and means for releasing the key set switch comprising a special wire separate from the wires utilized to control the automatic switching mechanism, said releasing means effective only after the 75 control for the automatic switching mechanism is started and after the circuit of said special wire is opened.

3. In a telephone exchange system, the combination of a calling subscriber's line, a called subscriber's line, means for interconnecting the lines including automatic switching mechanism in which said lines 80 terminate, an operator's keyboard having key sets and a signal thereon, key set switches associated with the keyboard and remote therefrom, said key set switches being adapted to connect the subscribers' lines to a key set for control of the automatic switching mechanism, means for sending impulses through said key set switch to operate the automatic switching mechanism and interconnect the subscribers' lines and a separate conductor and relays associated therewith for disabling the signal and releasing the said key set switch when the impulse sending device has finished sending 85 impulses and after said separate conductor is opened.

4. In a telephone exchange system, the combination of a calling subscriber's line, a 90 called subscriber's line, means for interconnecting the lines including automatic switching mechanism in which said lines terminate, an operator's keyboard having key sets and key sets thereon, key set switches 95 associated with the keyboard and adapted to connect subscribers' lines to the keyboard for control of the automatic switching mechanism, means for sending impulses to operate the automatic switching mechanism, 100 and a control circuit separate from the impulse sending circuit having a relay therein adapted to control the signals, and a release magnet for releasing the key set switch, said release magnet effective after the impulses 105 have been sent and after said separate conductor circuit is opened.

5. In a telephone exchange system, the combination of a calling subscriber's line, a called subscriber's line, means for intercon- 110

necting the lines including automatic switching mechanism, an operator's keyboard having key sets and signals arranged thereon, and remote from the automatic switching mechanism, key set switches associated with the automatic switching mechanism, three wire trunk circuits connecting the key set switches to the remote operator's keyboard, and means in one of said trunk circuits for controlling the signals at the operator's key sets and the release of the key set switches.

6. In a telephone exchange system, the combination of a calling subscriber's line, a called subscriber's line, means for interconnecting the lines including an automatic switching mechanism in which said lines terminate, an operator's keyboard having key sets and signals mounted thereon, said keyboard being remote from the automatic switching mechanism, key set switches associated with the automatic switching mechanism and remote from said keyboard, link circuits connecting the key set switches to the key sets at the keyboard, means for sending impulses over the link circuits in a predetermined order to operate the automatic switching mechanism to interconnect the subscribers' lines, and means for restoring the key set switch and actuating the signals comprising a conductor separate from the link circuit, a signal controlling relay included in circuit with said conductor, a circuit including a release magnet for the key set switch, and means in circuit with said conductor for controlling the circuit of the release magnet and operative when the impulse sending means has finished operating the automatic switching mechanism.

7. In a telephone exchange system, the combination of a calling subscriber's line, a called subscriber's line, means for interconnecting the lines including automatic switching mechanism in which said lines terminate, an operator's key set, a key set switch, means for sending impulses to operate the automatic switching mechanism, two wires adapted to connect the active key set switch to the impulse sending means and over which the impulses are transmitted in a predetermined order, and a third wire separate from the said two wires, means controlled by the third wire and in circuit therewith for effecting the release of the active key set switch, said two wires and said third wire constituting the sole connection between the active key set switch and impulse sending means.

8. In a telephone exchange system, the combination of a calling subscriber's line, a called subscriber's line, means for interconnecting the lines including switching mechanism in which said lines terminate, an operator's keyboard and key set, a key set switch, releasing means for the key set switch, two

wires connecting the key set switch to the keyboard over which the impulses are transmitted, a third wire controlling said key set releasing means, and means under the control of the operator for rendering said key set switch releasing means operative, the said two wires and third wire constituting the sole active connection between the operator's keyboard and the active key set switch and its releasing means.

9. In a telephone exchange system, the combination of a calling subscriber's line, a called subscriber's line, means for interconnecting the lines including automatic switching mechanism in which said lines terminate, an operator's keyboard and key set located remote from the automatic switching mechanism, a key set switch remote from the key set, means for sending impulses to operate the automatic switching mechanism including two wires adapted to be connected to the impulse sending means and over which impulses are transmitted, means for releasing the active key set switch after an impulse has been sent comprising a wire separate from said two wires and constituting the control circuit for a release magnet, and means associated with one of said two wires for controlling the operation of the release magnet, the said two wires and separate wire constituting the sole active connection between the operator's keyboard and the remote active key set switch and its releasing means.

10. In a telephone exchange system, the combination of a calling subscriber's line, a called subscriber's line, means for interconnecting the lines including automatic switching mechanism in which said lines terminate, an operator's keyboard and key sets thereon, key set switches arranged to connect the subscribers' lines to the keyboard for control of the automatic switching mechanism by the key sets including pairs of wires over which impulses are sent, means for sending impulses over said pairs of wires, means for releasing the key set switches, a separate wire controlling said releasing means, and a relay associated with one of said pairs of wires and operative when a single impulse has been sent over said wire to energize the releasing means.

11. In a telephone exchange system, the combination of a calling subscriber's line, a called subscriber's line, means for interconnecting the lines including automatic switching mechanism in which said lines terminate, an operator's keyboard and key set remote from said switching mechanism, a key set switch located with the automatic switching mechanism, wires connecting the key set switch to the operator's keyboard, means for transmitting impulses over one of said wires, a release magnet for the key set switch, a separate wire constituting a control circuit

for the release magnet, means including a relay arranged to disable the control circuit, a special relay temporarily connected to the wire over which the impulses are transmitted and adapted to be actuated when an impulse is transmitted over the wire to which it is connected whereby said release magnet is rendered operable by means under the control of the operator.

10 12. In a telephone exchange system, the combination of an operator's position, a calling subscriber's line terminating at said operator's position, a called subscriber's line, link circuits and automatic switching mechanism for interconnecting the lines, a second operator's position, means associated with the second operator's position for directing the action of the switching mechanism, trunk lines terminating at the first mentioned operator's position, and second operator's position, means for selecting the trunk calling and connecting the same to the second operator's position, and means for designating the selecting means employed for the selecting and connecting operation.

13. In a telephone exchange system, the combination of an operator's position, a calling subscriber's line terminating at said operator's position, a called subscriber's line, link circuits and automatic switching mechanism for interconnecting the lines, a second operator's position, means associated with the second operator's position for directing the action of the switching mechanism, trunk lines terminating at the first mentioned operator's position and second operator's position, special switches for associating the trunk lines with the second operator's position, and means for designating the special switch which shall connect a calling trunk line to the second operator's position.

14. In a telephone exchange system, the combination of a manual exchange switchboard provided with an operator's position, a calling subscriber's line terminating in the manual exchange switchboard, a called subscriber's line, means including automatic switching mechanism for interconnecting the lines, a second operator's position, means associated therewith for directing the action of the switching mechanism, trunk lines terminating at the manual switchboard and at the second operator's position, special automatic switches for connecting the trunk lines with said directing means, and means controlled by the second operator for designating the special automatic switch to be connected to the trunk line calling.

15. In a telephone exchange system, the combination of a manual exchange switchboard provided with an operator's position, a calling subscriber's line terminating in the manual exchange switchboard, a called

subscriber's line, means including automatic switching mechanism for interconnecting the lines, a second operator's position, means associated therewith for directing the action of the switching mechanism, trunk lines and an order wire terminating at the manual switchboard and at the second operator's position, a busy lamp and switching key for each trunk line, key set switches for connecting the trunk lines to said directing means, and means associated with each key set switch and under the control of the operator for designating the key set switch to be connected to the second operator's position.

16. In a telephone exchange system, the combination of a manual exchange switchboard provided with an operator's position, a calling subscriber's line terminating in the manual exchange switchboard, a called subscriber's line, means including automatic switching mechanism for interconnecting the lines, a second operator's position, means associated therewith for directing the action of the switching mechanism, trunk lines and an order wire terminating at the manual switchboard and at the second operator's position, key set switches for connecting the trunk lines to the second operator's position, means for operating said key set switches, and means associated with said operating means and controllable by the second operator for designating the key set switch which shall connect the trunk line calling to the second operator's position.

17. In a telephone exchange system, the combination of a manual exchange switchboard, a calling subscriber's line terminating at a jack in the manual switchboard, a semi-automatic operator's keyboard provided with key sets, a called subscriber's line, automatic switching mechanism for interconnecting the lines, means controlled by said key sets for directing the action of the switching mechanism, a key set switch, trunk lines terminating in jacks at the manual switchboard and in said key set switch, means for operating the key set switch including a relay for starting the operating means, a circuit for energizing said relay, and means controllable by the operator at the semi-automatic keyboard for controlling said circuit.

18. In a telephone exchange system, the combination of a manual exchange switchboard, a calling subscriber's line terminating in a jack at the manual exchange switchboard, a semi-automatic exchange remote from the manual exchange, link circuits and automatic switching mechanism at the semi-automatic exchange, a called subscriber's line terminating in the automatic switching mechanism, an operator's keyboard and key sets at the semi-automatic exchange, means associated therewith for directing the ac-

tion of the switching mechanism to interconnect the lines, key set switches, trunk lines terminating at the manual switchboard and in the key set switches, operating means 5 for the key set switches including a starting relay, a circuit for energizing said starting relay, and means including a magnet for disabling said circuit whereby the trunk calling may not become connected to the key 10 set switch disabled.

19. In a telephone exchange system, the combination of a first operator's position, calling subscribers' lines terminating at the first operator's position, a second operator's 15 position, a keyboard and key sets at the second operator's position, calling subscribers' lines terminating at the second operator's position, means for interconnecting the subscribers' lines operable from the second operator's position, automatic switches 20 associated with the second operator's position, trunk lines terminating at the first operator's position and in the automatic switches and second operator's position, and 25 means for operating the automatic switches comprising starting means, a circuit for controlling said starting means and means controllable by the second operator for controlling said circuit.

30 20. In a telephone exchange system, the combination of a calling subscriber's line, a called subscriber's line, switching mechanism for interconnecting the lines including an automatic switch, releasing means 35 for said switch, and means independent of any of the circuits of the line called for preventing the operation of said releasing means.

21. In a telephone exchange system, the 40 combination of a calling subscriber's line, a called subscriber's line, switching mechanism for interconnecting the lines including automatic switches, means for releasing the switches, and means independent of any 45 of the circuits of the line called for preventing the operation of said releasing means at will.

22. In a telephone exchange system, the 50 combination of a calling subscriber's line, a called subscriber's line, switching mechanism including an automatic switch for interconnecting said lines, an operator's position, means at said position for directing the operation of said automatic switch, 55 means for releasing said automatic switch, the operation of said releasing means depending upon the position assumed by said switch under the influence of said directing means.

60 23. In a telephone exchange system, the combination of a calling subscriber's line, a called subscriber's line, means for interconnecting the lines including automatic switching mechanism, an operator's position, means for releasing the switching 65

mechanism, and means at the operator's position for directing the action of the switching mechanism and disabling said releasing means at will.

24. In a telephone exchange system, the 70 combination of a calling subscriber's line, a called subscriber's line, automatic switching mechanism for interconnecting the lines including a primary switch and a first selector switch, releasing means for the 75 switches, an operator's position, means for directing the operation of the switching mechanism and for preventing the release of said switches at will.

25. In a telephone exchange system, the 80 combination of a calling subscriber's line, a called subscriber's line, switching mechanism for interconnecting the lines including a primary automatic switch and connector switch, means for releasing the primary switch, means for directing the operation of the switching mechanism, and means independent of any of the circuits of the called line for disabling said releasing 85 means at will.

26. In a telephone exchange system, the 90 combination of a calling subscriber's line, a called subscriber's line, switching mechanism for interconnecting the lines including an automatic switch having banks of 95 contacts, certain of contacts being special and without connection to said lines, releasing means for said automatic switch and means for operating the automatic switch to connect the releasing means with 100 the special contacts whereby the releasing means is disabled.

27. In a telephone exchange system, the 105 combination of a calling subscriber's line, a called subscriber's line, switching mechanism for interconnecting the lines including an automatic selector switch having open contacts, an operator's position, releasing means for the selector switch including a circuit terminating in said switch, and 110 means for directing the operation of the switching mechanism to connect said circuit to the open contacts whereby the releasing means is disabled.

28. In a telephone exchange system, the 115 combination of a calling subscriber's line, a called subscriber's line, switching mechanism for interconnecting the lines, including an automatic switch having banks of contacts therein, the contacts of one of said 120 banks being normally open, signaling means connected to another bank of contacts, releasing means for the automatic switch, and means for directing the operation of the switch so as to connect the releasing 125 means to an open contact and disable the same and simultaneously operate said signaling means.

29. In a telephone exchange system, the combination of a calling subscriber's line, 130

a called subscriber's line, automatic switching mechanism for interconnecting the lines, a selector switch having banks of contacts, certain of said contacts being open, signaling means connected with other contacts, releasing means including a circuit terminating in the selector switch, and a magnet in said circuit, an operator's position, means at the operator's position for directing the action of the selector switch and arranged to operate said switch so as to connect the said circuit with the open contacts and simultaneously energize the signaling means whereby the releasing means is disabled and said signal is operated.

30. In a telephone exchange system, the combination of a calling subscriber's line, a called subscriber's line, automatic switching mechanism for interconnecting the lines including a primary switch and a first selector switch, an operator's keyboard and key sets, key set switches associated therewith, trunk lines terminating in the primary switch and key set switches, said selector switch being provided with banks of contacts, certain contacts being open, lamps connected to certain other contacts, wipers on the switch adapted to connect with the contacts, releasing means for the first selector switch comprising a circuit connected to one of said wipers, a release magnet in said circuit, a separate circuit connected to another wiper arranged to cooperate with the contacts to which said lamps are connected, and means for directing the operation of the selector switch to interconnect the lines and at will to operate the said switch so that said wiper connected to the release circuit will engage upon an open contact and the wiper connected to said separate circuit will engage a contact connected to a lamp whereby the release circuit is maintained in disabled condition and the signal is given to an attendant.

45. 31. In a telephone exchange system, the combination of means for producing impulses, a step-by-step switch adapted to be connected with said impulse producing means, means for determining the number of impulses to be transmitted, means for controlling the connection of said impulse producing means to the step-by-step switch arranged so that the impulses may be transmitted in a certain order, and means for altering the order of transmission of said impulses.

32. In a telephone exchange system, the combination of means for producing impulses, a link circuit, an automatic switch adapted to connect said impulse producing means with said link circuit, means for determining the order and number of impulses transmitted, means for controlling the connection of said impulse producing means to

the automatic switch, and means for altering the order and number of impulses transmitted.

33. In a telephone exchange system, the combination of an operator's position, means associated therewith for producing impulses in recurring cycles, a step-by-step switch adapted to be actuated one step each cycle, means adapted to connect said impulse producing means to the step-by-step switch, means at the operator's position for determining the order of the impulses to be transmitted and for controlling the connection of said impulse producing means to the step-by-step switch, and means under the control of the operator for altering the order of transmission of said impulses.

34. In a telephone exchange system, the combination of means for producing impulses, a step-by-step switch comprising banks of contacts, means for determining the number of impulses to be transmitted, means associated with one of said banks of contacts for controlling the connection of said impulse producing means to the switch and the order of transmission of said impulses, and means associated with another bank of contacts for altering the connection of the determining means to the switch so that the order of impulses transmitted will be altered.

35. In a telephone exchange system, the combination of calling subscribers' lines terminating at an operator's position in a semi-automatic exchange, called subscribers' lines terminating at an operator's position in a manual exchange, trunk lines terminating at the manual operator's position and in said semi-automatic exchange, automatic switching mechanism for connecting the calling subscribers' lines to said trunk lines including a first selector, and a connector switch in which the trunk lines terminate, and means for directing the action of said first selector and connector switch comprising means for producing impulses, mechanism for connecting the impulse producing means to the switches, means for determining the order of the impulses transmitted by said connecting mechanism, and means for controlling the operation of said connecting mechanism.

36. In a telephone exchange system, the combination of calling subscribers' lines terminating at a semi-automatic exchange, an operator's position at said exchange, wanted subscribers' lines, a part of which terminate in the semi-automatic exchange, others terminating at an operator's position in a manual exchange, automatic switching mechanism for interconnecting the subscribers' lines which terminate in the semi-automatic exchange, trunk lines terminating at the operator's position in the manual exchange, auto-

matic switching mechanism for interconnecting the wanted lines in the manual exchange with the subscribers' lines in the automatic exchange including a special connector switch in which said trunk lines terminate, and means for directing the operation of all of the switching mechanism comprising means for producing impulses, means for determining the order of transmission of said impulses to direct the operation of either the switching mechanism for interconnecting the lines terminating in the automatic exchange or the special switch, means for controlling the connection of the impulse producing means to the automatic switching mechanism arranged so that the automatic switching mechanism for interconnecting the subscribers' lines terminating at the semi-automatic exchange are directed at one position of the determining means so that the special switch in which the trunk lines terminate may be directed at a certain position of said determining means.

37. In a telephone exchange system, the combination of automatic switching mechanism, means for producing impulses, switching means for connecting said impulse producing means to direct the automatic switching mechanism, means for determining the number of the impulses transmitted to said automatic switching mechanism, and means for altering the condition of said connecting means so as to change the number of impulses transmitted to the switching mechanism.

38. In a telephone exchange system, the combination of calling subscribers' lines, called subscribers' lines, means for interconnecting the lines including automatic switching mechanism, means for directing the operation of said switching mechanism, means interposed between the directing means and the automatic switching mechanism for altering the effect of the directing means.

39. In a telephone exchange system, the combination of a calling subscriber's line, a called subscriber's line, means for connecting the lines including automatic switching mechanism, means for directing the operation of the automatic switching mechanism including an impulse sending device, means for determining the order of transmission of said impulses, means for connecting the impulse sending means to the switching mechanism to operate the latter, actuating means for said connecting means, and means operable after the determining means is disabled for energizing said actuating means to return the connecting means to normal position.

40. In a telephone exchange system, the combination of means for producing impulses, a step-by-step switch having a bank

of contacts adapted to be connected to said impulse producing means, means for determining the number or order of impulses to be transmitted by said impulse producing means including connections terminating in another bank of contacts, and means for altering the connections so that the order or number of impulses transmitted will be changed.

41. In a telephone exchange system, the combination of an operator's position, means for producing impulses, a step-by-step switch adapted to be connected with said impulse producing means, a keyboard and key set at said operator's position for determining the order and number of impulses transmitted and separate means at the operator's position for changing the operation of said step-by-step switch to alter the number of impulses transmitted.

42. In a telephone exchange system, the combination of a calling subscriber's line terminating in a semi-automatic exchange, called subscribers' lines part of which terminate in a manual exchange and part of which terminate at said automatic exchange, automatic switching mechanism including first selector, second selector, and connector switches for interconnecting the lines terminating in the semi-automatic exchange, means including trunk lines, first selector and connector switches in which said trunk lines terminate for interconnecting the calling subscriber's line with a line terminating in the manual exchange, and common means for directing the operation of the switching mechanism including the following instrumentalities: means for producing impulses, a step-by-step switch adapted to connect the impulse producing means to the switching mechanism, an operator's keyboard and key set for determining the number and order of impulses to be transmitted, and including connections in said step-by-step switch, and means for altering the order and number of impulses transmitted to the switching mechanism.

43. In a telephone exchange system, the combination of means for producing impulses, a step-by-step switch adapted to be connected with said impulse producing means, said step-by-step switch having banks of contacts, one of said banks of contacts being connected to a circuit over which the impulses are transmitted and impulse producing means is adapted to be connected, means for determining the order and number of impulses to be transmitted including connections terminating in a second bank of contacts on said switch and adapted to control the connection of the impulse sending means to said circuit over which the impulses are transmitted, and means for

altering the connections in said second bank of contacts so that the order of transmission of said impulses may be altered including a relay, and means for restoring the switch to normal position comprising a third bank of contacts on said switch and a release magnet associated therewith.

44. In a telephone exchange system, the combination of a manual switch-board, a calling subscriber's line terminating in a jack on said manual switch-board, a called or wanted subscriber's line, automatic switching mechanism, trunk lines terminating in other jacks on said manual switch-board and in said automatic switching mechanism, a semi-automatic operator's keyboard and key sets, key set switches associated therewith and arranged to connect the key sets to the trunk lines, and an intermediate switch adapted to pick out an idle key set switch and arranged to be actuated when any one or a number of operators at the manual switch-board plug into jacks associated with trunks connected to said intermediate switch, and means actuated when the intermediate switch picks out an idle key set switch for dissociating the intermediate switch and rendering the same available for another calling trunk.

45. In a telephone exchange system, the combination with a first operator's position, a subscriber's calling line terminating at said operator's position, called or wanted subscribers' lines, means for interconnecting the lines including automatic switching mechanism in which the called or wanted subscribers' lines terminate, and trunk lines terminating at the first operator's position, a second operator's position, means for connecting the trunk lines to the second operator's position comprising automatic switches and means associated with a plurality of trunks and adapted to be actuated when any one of said trunks call to select one of said key set switches, and means associated with said selecting means and rendered active at intervals to disable the selecting means so that the latter will respond to any other active trunk of the group with which it is associated.

46. In a telephone exchange system, the combination of a first operator's position, a calling subscriber's line terminating at said position, a called or wanted subscriber's line, means for interconnecting the lines including automatic switching mechanism in which said wanted subscriber's line terminates and trunk lines terminating at the first operator's position, a second operator's position remote from said first operator's position, mechanism for connecting the second operator's position with said trunk lines including automatic switches, an intermediate switch and its operating means associated with a group of trunks and rendered operative when any one of said groups is energized to

select an idle automatic switch to connect a calling trunk with a second operator's position, and means associated with said intermediate switch for disabling the latter at intervals comprising a relay rendered active at intervals to disable the operating means of said intermediate switches.

47. In a telephone exchange system, the combination of a first operator's position, a calling subscriber's line terminating at said position, a called or wanted subscriber's line, means for interconnecting the line including link circuits and automatic switching mechanism in which the call to one line terminates, trunk lines terminating at said first operator's position and in the automatic switching mechanism, a second operator's position remote from the first operator's position and including a key-board and key sets, impulse sending means associated with the second operator's position, a trunk line terminating at the second operator's position and comprising two conductors from which the impulses are transmitted and a third control conductor, automatic key set switches in which said conductors terminate and adapted to connect the trunk lines to the key-board, an intermediate automatic switch, means for operating said intermediate switch when any one of a group of trunks is energized to connect said calling trunk to an idle key set switch, and means for disabling said intermediate switch and its operating means comprising a relay controlling the circuit of the operating means and arranged to be operated at intervals whereby a plurality of said group of trunk lines may be active but prevented from maintaining the intermediate switch operating means in operative condition over an indefinite period of time.

48. In a telephone exchange system, the combination of a first operator's position, a calling subscriber's line terminating at said position, a called subscriber's line, means for interconnecting the line including automatic switching mechanism in which the called subscriber's line terminates and trunk lines terminating at said first operator's position, a second operator's position, key set switches associated therewith, an intermediate automatic switch associated with the trunk calling and adapted to select an idle key set switch, and means under the control of the second operator for designating the key set switch and for starting the operation of the intermediate switch to select the switch designated and connect the designated switch to the trunk calling.

49. In a telephone exchange system, the combination of subscribers' lines, automatic switching mechanism for interconnecting the lines, an operator's position and means controlled by the operator for originating a call comprising a special circuit, means included

in said special circuit for operating a key set switch associated with the operator's position, and means for directing the operation of the switching mechanism to interconnect 5 the lines.

50. In a telephone exchange system, the combination of subscribers' lines including a party line automatic switching mechanism in which said lines terminate, an operator's 10 key board and key sets, means for directing the operation of the switching mechanism associated with said key sets, a special circuit controlled by the operator, key set switches associated with the key sets, and means for 15 controlling the special circuit to select an idle key set whereby said operator may originate a call.

51. In a telephone exchange system, the combination of a calling subscriber's line, a 20 called subscriber's line, means for interconnecting the lines including automatic switching mechanism, an operator's position, an auxiliary switch associated with the automatic switching mechanism, a three wire 25 trunk circuit connecting the auxiliary switch to the operator's position, and means associated with said position for controlling the automatic switching mechanism and the release of the auxiliary switch over said three 30 wire trunk circuit.

52. In a telephone exchange system, the combination of a calling subscriber's line, a called subscriber's line, means for interconnecting the lines including automatic 35 switching mechanism, an operator's position, auxiliary switching mechanism arranged to connect the subscriber's line to the position for control of the automatic switching mechanism from said position, releasing 40 means for the auxiliary switching mechanism, three conductors extending from said auxiliary switching mechanism to said operator's position, means associated with said position for controlling the operation of the 45 automatic switching mechanism and the release of said auxiliary switching mechanism.

53. In a telephone exchange system, the combination of calling subscribers' lines terminating at a semi-automatic exchange, an operator's position at said exchange, wanted subscribers' lines terminating at an operator's position in a manual exchange, trunk lines terminating at the operator's position in the manual exchange, automatic switching mechanism for interconnecting the wanted lines in the manual exchange with subscribers' lines terminating in the semi-automatic exchange including a special 55 switch in which said trunk lines terminate, means associated with the operator's position in the semi-automatic exchange for directing the action of the switching mechanism including the special automatic switch.

54. In a telephone exchange system, the combination of calling subscribers' lines terminating at an operator's position in a semi-automatic exchange, called subscribers' lines terminating at an operator's position in a manual exchange, trunk lines terminating at 65 the manual operator's position and extending to said semi-automatic exchange, automatic switching mechanism for connecting the calling subscribers' lines to said trunk lines including a first selector, and a connector 70 switch in which the trunk lines terminate, and means in said semi-automatic exchange for directing the action of the first selector and connector switches comprising means for producing impulses, mechanism for connecting the impulse producing means to the switches, means for determining the order of the impulses for controlling the operation of said switches.

55. In a telephone exchange system, the combination of subscribers' lines, automatic switching mechanism for interconnecting the lines, an operator's position having an associated automatic switch, means controlled by the operator for causing the operation of said automatic switch to effect connection with the automatic switching mechanism, and means for thereafter directing the operation of switching mechanism to interconnect the lines.

56. In a telephone exchange system, the combination of subscribers' lines, automatic switching mechanism for interconnecting said lines, a main office and an operator's position thereat, a branch office, means controlled over said operator's position for originating a call at the branch office to register the same on said position, means at said position for operating said switching mechanism to interconnect said lines.

57. In a telephone exchange system, the combination of a main office, of an operator's position at said office for registering calls, a branch office, means controlled over said operator's position for originating a call at 100 the branch office to register the same on said position.

58. In a telephone exchange system, the combination with an operator's position, a calling subscriber's line terminating at said position, a called subscriber's line, automatic switching mechanism for interconnecting the lines, a second operator's position, means controlled at the first operator's position for causing the association of the second operator's position with said automatic switching mechanism, means associated with the second operator's position for thereafter directing the action of the automatic switching mechanism, and means associated with the first operator's position for supervising the connection established by said switching mechanism.

59. In a telephone exchange system, the combination with an operator's position, trunk lines at said position terminating in automatic switching mechanism, means at said position for selecting said trunk lines, a second operator's position, means for connecting the selected trunk lines to the second operator's position, and means associated with said trunk lines operated when a trunk

is selected for disabling said connecting means for a predetermined time interval.

In testimony whereof I affix my signature in presence of two witnesses.

Witnesses:

JOSEPH L. WRIGHT.

ARTHUR L. BRYANT,
E. S. GREENEWALD.
